UNITED STATES PATENT OFFICE.

FREEMAN C. ROBINSON AND JOHN F. JACOBY, OF MINNEAPOLIS, MINNESOTA, AS
SIGNORS TO O. B. MCCLINTOCK COMPANY, OF MINNEAPOLIS, MINNESOTA, A COR-
PORATION OF MINNESOTA.

BURGLAR ALARM.

Application filed December 22, 1919. Serial No. 346,596.

To all whom it may concern:

Be it known that we, FREEMAN C. ROBINSON and JOHN F. JACOBY, citizens of the United States, residents of Minneapolis, county of Hennepin, State of Minnesota, have invented certain new and useful Improvements in Burglar Alarms, of which the following is a specification.

In banks and business houses where day-light robberies or holdups are apt to occur, devices have been provided to be operated by the foot of a bank teller or cashier or other person for the purpose of closing an electric circuit and sounding a distant alarm to warn police officials or others than a robbery is taking place in the building where the alarm mechanism is located. This alarm device actuated usually by the downward movement of a button has been objectionable, as it is likely to be operated unintentionally, as when a person might accidentally press the foot upon the alarm pedal or button connected with the alarm. Sometimes alarms of this kind have been put in operation by a dog lying down on the alarm button or pedal and actuating it sufficiently to close the electric circuit. The danger of thus inadvertently sounding the alarm in a bank or other building so equipped has led to the discontinuance of the use of such devices on the part of the owner.

The object of our invention is to provide a device to be actuated by the foot of a teller, clerk or other person and so arranged or constructed that resting the foot on the same or a downward pressure or a blow will have no effect whatever on the closing mechanism.

Other objects of the invention will appear from the following detailed description.

The invention consists generally in various constructions and combinations, all as hereinafter described and particularly pointed out in the claims.

In the accompanying drawings forming part of this specification,

Figure 1 is a side elevation of the alarm device showing the manner of operating it with the foot to close the circuit.

Figure 2 is a sectional view on the line 2—2 of Figure 1, showing the device in its operative position with the circuit broken,

Figure 3 is a view showing the device in its inoperative position, with the circuit open,

Figure 4 is a similar view with the device 55 operated and the circuit closed,

Figure 5 is a sectional view on line 5—5 of Figure 3.

In the drawing, 2 represents the floor of a room where the device is installed. 3 represents posts having a flanged base 4 adapted to rest upon the floor and secured thereto by suitable means, such as screws 5. The posts 3 are hollow and are provided with an insulating bushing 6. A conducting pin 7 is 65 mounted in the wall of the post and projects through the insulation 6 and is pressed inwardly by yielding means, such as a spring 8. 9 represents a stud mounted to slide in the post 3 and insulated therefrom by the 70 bushing 6 and having an insulating portion 10 on which the pin 7 rests when the device is inactive. The stud has a flange 11 at its lower end and a sound-deadening washer 12 is seated on this flange in position to silently stop the upward movement of the stud 9 and the parts attached thereto when the stud is raised. A pin 13 is tapped into the lower end of the stud, securing the insulation 10 and the flange 11 in place and is 75 slidable in the hole 14 in the floor and forms an electrical connection between the stud 9, flange 11 and electrical circuit 15 leading to a suitable signalling device 16' located at any suitable point, preferably at a distance from the 80 room to be guarded.

16 is a similar conductor which we have shown preferably connected to the base of the post. The upper end of the stud 9 projects into the cylindrical foot rail 17 and is 85 secured thereto by suitable means, such as a screw 18. The post at the other end of the rail is equipped in a similar manner and its stud is connected to the rail in the same manner as described with reference to Figure 2. 90 Normally, the circuit will be broken at the point where the pin 7 contacts with the insulation 10 and the rail being in its depressed position, cannot be operated by pressure thereon from the foot, or by the weight 100 of an article, as when something may be dropped upon it, but will remain in its normally depressed position, as shown by Figure 2, and in this position the electric circuit will be positively broken and there will be 105 no danger of the alarm being sounded. In case, however, the person in the bank or business house wishes to sound the alarm, the foot

being inserted under the rail, as shown in Figure 1, a slight tilt of the foot on the heel of the shoe will lift the rail from the full line position shown in Figures 1 and 2 to the dotted line position in said figures. By this movement the flange 11 will be raised so that the stud 9 contacts with the pin 7 which is in electrical contact with one side of the battery. The circuit will then be closed and the alarm sounded. The rail is so mounted that there will be sufficient clearance between it and the top of the shoe to allow the clerk, cashier, or other person standing or seated at the counter to easily slip the foot under the rail and if such person is ordered to throw up his hands by a robber he can in the act of straightening up, while standing or if seated in a chair, at the same time that his hands are thrown up, tilt his foot slightly on the heel, sufficiently to raise the rail and close the circuit while no movement to produce such result could be noticed by the robber. The action of the foot would be so slight that the only movement of the leg noticeable would be that incidental to the straightening up of the body or the throwing up of the hands in compliance with the command of the robber. Devices that require pressure of the foot or are operated by the knee demand a forward or lifting movement or a hand action of such a nature and extent that it is likely to be instantly detected by the robber, who of course would immediately shoot the person so attempting to operate the alarm. Our invention is so contrived that the mere act of tilting the body back or throwing up the hands allows or provides for the simultaneous tilting of the foot sufficient to raise the rail and close the circuit. It is obviously of great importance that the alarm should be easily and silently operated with no extra movement or effort

on the part of the person in the bank, and our experiments have demonstrated that this rail can be raised with a slight movement of the foot and such a movement that can not be detected by the person attempting to commit the robbery. The alarm, of course, would be sounded at a distance so that the robber would not in any way connect the act of the person throwing up his hands with the sounding of the alarm.

A feature of importance in this device is that when the rail is raised and the circuit closed, the alarm will be sounded continuously until the current is broken by the manual return of the rail to its normal position.

We claim as our invention:

1. A device of the class described comprising a foot rail, guides supporting said foot rail a sufficient distance from the floor to allow the insertion of the toe of the foot between the floor and the rail, tilting of the foot on the heel engaging the toe with and lifting said rail, said rail and guides having opposing contact surfaces and said rail in its normal position forming a non-depressible foot rest.

2. A circuit closer comprising a foot rail and a stud thereon, a guide wherein said stud is vertically slidably, said rail being normally supported a suitable distance from the floor to allow the insertion of the toe of the foot between the rail and the floor, tilting of the foot on the heel engaging the toe with and lifting said rail and sliding said stud in its guide, said stud and guide having opposing contact surfaces and said rail in its normal position forming a non-depressible foot rest.

In witness whereof, we have hereunto set our hands this 16th day of December, 1919.

FREEMAN C. ROBINSON.
JOHN F. JACOBY.
